UNITED STATES PATENT OFFICE.

DANIEL R. BRADLEY, OF NEW YORK, N. Y.

DESIGN FOR A PERFUMERY-HOLDER.

SPECIFICATION forming part of Design No. 22,624, dated July 18, 1893.

Application filed March 28, 1893. Serial No. 468,051. Term of patent 3½ years.

To all whom it may concern:

Be it known that I, DANIEL R. BRADLEY, a citizen of the United States, and a resident of the city, county, and State of New York, have 5 invented and produced a new and original Design for a Perfumery-Holder, of which the following is a specification, reference being had to the accompanying drawing, which is a perspective view of a receptacle embodying 10 the design.

The leading feature of the design for a perfumery holder consists in the unitary design shown, viz: elongated receptacle proper for the liquid perfumery having somewhat the contour of a cannon and provided with a stopper. This receptacle proper rests in a nearly horizontal position on a rolling support somewhat 15 resembling the carriage of a cannon.

A is the receptacle proper for the perfumery, which has an elongated, tapered form, and 20 a is the stopper which closes it. The support consists of an ornamental plate, B, having a curved form, and wheels, C, simulating the wheels on the carriage of a cannon.

What I claim is—

The design for a perfumery holder as herein shown and described.

In witness whereof I have hereunto signed my name in the presence of two subscribing witnesses.

DANIEL R. BRADLEY.

Witnesses:

HENRY CONNETT,
PETER A. ROSS.
